UNITED STATES PATENT OFFICE

160,310

ROOM HUMIDIFIER

Abrom L. Feldman and Ira Schneid, Atlanta, Ga.,
assignors to Puritan Sales Company, Atlanta, Ga.

Application December 1, 1949, Serial No. 6,352

Term of patent 14 years

(Cl. D62—4)

To all whom it may concern:

Be it known that we, Abrom L. Feldman and Ira Schneid, both citizens of the United States of America, and residing, respectively, in Atlanta, Fulton County, State of Georgia, have invented a new, original, and ornamental Design for a Room Humidifier, of which the following is a specification, reference being had to the accompanying drawing, forming a part thereof.

In the drawing,

We claim:

The ornamental design for a room humidifier, as shown.

ABROM L. FELDMAN.
IRA SCHNEID.
